COMBINED SHOE POLISH CONTAINER, APPLICATOR, AND SHOE BRUSH

Allan Withington Halladay, Cranston, R. I.

Application October 8, 1956, Serial No. 43,270

Term of patent 14 years

(Cl. D9—2)

I claim:

The ornamental design for a combined shoe polish container, applicator and shoe brush, as shown.
